CLAIM

The ornamental design for a computer cabinet as shown and described.

DESCRIPTION

FIG. 1 is a perspective view of a first embodiment of the computer cabinet showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right-side elevation view thereof; and

FIG. 7 is a left-side elevation view thereof.

FIG. 8 is a perspective view of a second embodiment of the computer cabinet showing our new design;

FIG. 9 is a front elevation view thereof;

FIG. 10 is a rear elevation view thereof;

FIG. 11 is a top plan view thereof;

FIG. 12 is a bottom plan view thereof;

FIG. 13 is a right-side elevation view thereof; and,

FIG. 14 is a left-side elevation view thereof.

(Continued)

The broken lines in the figures represent portions of the computer cabinet that form no part of the claimed design.
